CLAIM

The ornamental design for a firearm forend, as shown and described.

DESCRIPTION

FIG. 1 is a perspective view of the firearm forend of the present invention;

FIG. 2 is a bottom view of the firearm forend of FIG. 1;

FIG. 3 is a top view of the firearm forend of FIG. 1;

FIG. 4 is a right side view of the firearm forend of FIG. 1;

FIG. 5 is a left side view of the firearm forend of FIG. 1;

FIG. 6 is a front view of the firearm forend of FIG. 1; and,

FIG. 7 is a back view of the firearm forend of FIG. 1.

The broken line showing of portions of the firearm forend in FIGS. 3, 6 and 7 is included for the purpose of illustrating environment and forms no part of the claimed design.
